COMPOSITE MAILING ENVELOPE

Harold S. Scott, Alliance, Ohio

Application October 18, 1950, Serial No. 190,691

4 Claims. (Cl. 229—92.8)

1

This invention relates to mailing pieces, an object thereof being to provide a combined multiple panel envelope providing a sender's envelope, a return envelope, communication-bearing sections, and a coin holder, all embodied in a single composite foldable blank.

Another object is to provide a composite business transaction conduction envelope composed of a plurality of united and relatively foldable panels or sections which, when normally assembled, provide one or more internal letter panels bearing sales messages or other appeals, and which are capable of being removed from the envelope blank by the addressee, the remaining blanks being formed and arranged so that the same may be folded to produce a sealable return envelope adapted for use by the original addressee to transmit a reply with appropriate coins to the message or appeal of the original addressor.

A further object of the invention is to provide a two-way mailing piece of this character which may be economically produced from a blank comprising a flat die-cut sheet, the latter presenting a novel arrangement of foldable and detachable panels so formed as to provide economies in the original cost of the mailing piece and also in postal transmission rates.

For a further understanding of the invention, including additional objects and advantages thereof, reference is to be had to the following description and the accompanying drawing, wherein:

Fig. 1 is a plan view of the paper blank or sheet from which the mailing envelope of the present invention is formed;

Fig. 2 is a similar view disclosing the blank when partially folded to overlap the coin and body sections;

Fig. 3 is a detail vertical sectional view taken on the line 3—3 of Fig. 1;

Fig. 4 is a plan view of the blank showing the condition of the same after the communication sections have been folded into overlapping relationship with the coin and body sections;

Fig. 5 is a similar view disclosing the appearance of the main envelope prior to the folding and sealing of its addressing section;

Fig. 6 is a view disclosing the finally folded and sealed main envelope when the same is in condition for mailing to an original addressee.

Referring more particularly to the drawings, my improved composite envelope is formed from a blank comprising a die-cut single sheet of paper of appropriate weight and grade. The blank is

2

cut to present a multiplicity of united rectangular panels or sections, each adapted for a definite purpose. In this instance, the numeral 10 designates the body section of the envelope which is joined along its lower side, by means of a weakened, scored or perforate line 11, with a panel or section 12. To one side of this panel there is adapted to be applied the name and address of an original addressee, as disclosed at 13 in Fig. 6. The address section 12 may have its lower edge provided with a gummed sealing flap 14, or other tying or securing means.

Along its upper edge, as the blank is viewed in Fig. 1, the body section adjoins a return address panel or section 15, the latter having its upper edge foldably joined with an adhesive-containing sealing flap 16 or its equivalent. The panels 10, 12 and 15 are of approximately the same dimensions.

20 The body section 10 and return address section 15 are along their left edges, as viewed in Fig. 1, detachably joined with communication and letter sections 17 and 18. On each of these sections, there may be printed or written a sales 25 message or other matter transmitted by the original addressor to the original addressee. The communication or letter sections 17 and 18 are preferably joined with the sections 10 and 15 by weakened or perforated lines 19, so that the same may be detached from the blank after being received by the original addressee.

At the right of the blank, as viewed in Fig. 1, the sections 10 and 15 carry a pocket-forming section 20 and a coin-receiving and transmitting section or panel 21. These sections on the upper side thereof, as viewed in Fig. 1, have their marginal portions provided with an adhesive indicated at 22. The under or opposite face of the section 21, as shown in Fig. 3, particularly, is provided with a paperboard coin-carrying card 23, which is adhesively joined with the panel 21 to produce, in effect, a single panel. The coin-carrying card or panel 23 is formed to provide a suitable number of punched-out portions as indicated at 24, against which the edges of a coin abut, so that a coin may be received and gripped in each of the punched-out portions and held against movement for safety in mail transmission.

50 In use, the blank is formed, as shown in Fig. 1, with a message printed or otherwise applied on the communication sections 17 and 18. In folding the envelope so that the same may be used to transmit the message on the sections 17 and 18 to an original addressee, the sections 20

and 21 are turned so that they engage flatly upon the sections 15 and 10, respectively, as indicated in Fig. 2. At this time a sealing of the folded sections is effected by moistening and joining the adhesive strips, indicated at 22, with the panel sections 10 and 15. The section 20 cooperates with the section 15 to form a pocket 25 which may be used by the original addressee to receive a separate letter sheet or currency.

After the sections 20 and 21 have been adhesively joined with the sections 15 and 10, the communication-bearing sections 17 and 18 are folded over from left to right until they overlap the previously folded sections 10, 15, 20 and 21, as indicated in Fig. 4. When this has been accomplished, the sections 15, 17 and 20 are folded downwardly over the body section 10, as disclosed in Fig. 5, and finally the main or original envelope is completed by folding the address section 12 upwardly so that the address-receiving face 13 will be disposed on top of the envelope, thereby producing a mailing piece of standard dimensions. The flap shown at 14 instead of being adhesively sealed may be mechanically joined by a clip, tying cord or the like not shown, with the body of the envelope, so that the communication, as mailed by the original addressor to the original addressee, may be opened by postal authorities while in transit, enabling the same to be transmitted at a lower postal rate than a sealable letter. The original envelope, however, may be sealed by the adhesive on the flap 14 if it should be so desired.

After the original envelope has been received by the original addressee, and if it should be the desire of the addressee to reply with a transmission of money, said addressee may sever the sections 12, 17 and 18 along their perforated lines 11 and 19 from the body and address sections 10 and 15. Coins may be inserted in the carrier card 23 and a letter or currency placed in the pocket 25. The name of the original addressee and address may be written on the front side of the section 20 in the space provided therefor at 26. The return envelope is then formed and sealed by folding the sections 15 and 20 downwardly upon the carrier card section or panel 23. The thus folded sections are secured permanently by the adhesive strips indicated at 27 in Fig. 2 and arranged marginally on the front surfaces of the panel sections 20 and 21. The flap 16 may then be turned down and sealed, closing the return envelope on all its sides, and rendering the same capable of being transmitted to the original addressor as first class mail. The coin-receiving openings in the carrier card 23 are so disposed that the same will not interfere with postal dating and stamp-cancelling operations, as the latter will be disposed and performed above the region in which the coin openings or pockets are present in the card 23.

The coin carrier 23 is preferably made so that it possesses the same thickness of the coin or coins to be inserted therein. In other words, the coins fit in a flush manner with the outer surfaces of the die-cut coin section.

It will be understood that certain features and sub-combinations are of utility and may be employed without reference to other features and sub-combinations. This is contemplated by and is within the scope of my claims. It is further obvious that various changes may be made in details within the scope of my claims without departing from the spirit of my invention. It is,

therefore, to be understood that my invention is not to be limited to the specific details shown and described.

I claim:

5. A composite forwarding and return postal envelope, comprising: a back-forming section of rectangular configuration, a primary-address receiving section foldably joined with said back section along one of the longitudinal margins 10 of the latter, a return address-bearing section joined with said back-forming section along its longitudinal margin opposite to that with which said primary-address section is joined, communication-receiving sections having inner side regions foldably joined with the back and return address sections along one side of each of the latter sections, rectangular coin-carrying and pocket-forming sections projecting laterally from and foldably joined with the opposite side margins 20 of the back and return sections as regards said communication-receiving sections, said coin-carrying and pocket-forming sections having top surfaces marginally coated with an adhesive for uniting said last-named sections with the back 25 and return address sections when said envelope is operatively folded, and a perforate coin-receiving card joined with said coin-carrying section on one side thereof.
2. A composite forwarding and return postal envelope as defined in claim 1, and wherein all the sections of the envelope are of substantially rectangular configuration and with the exception of the pocket-forming section possess substantially equivalent dimensions.
3. A composite forwarding and return postal envelope as defined in claim 1, and wherein said coin-receiving card is provided with an imperforate region above the coin perforations therein, said imperforate region providing a reinforcing 40 base in registry with the stamp-receiving region of each of the address sections when the envelope is operatively folded.
4. A composite forwarding and return postal envelope, comprising: a back-forming section of rectangular configuration, a primary-address receiving section foldably joined with said back section along one of the longitudinal margins 45 of the latter, a return address-bearing section joined with said back-forming section along its longitudinal margin opposite to that with which said primary-address section is joined, foldable adhesive-containing flaps formed with the outer longitudinal margins of the primary and address sections, communication-receiving sections having inner side regions foldably and detachably joined with the back and return address sections along one side of each of the latter sections, rectangular coin-carrying and pocket-forming sections projecting laterally from and foldably 50 joined with the opposite side margins of the back and return sections as regards said communication-receiving sections, said coin-carrying and pocket-forming sections having top surfaces marginally coated with an adhesive for uniting said last-named sections with the back and return address sections when said envelope is operatively folded, and a perforate coin-receiving card joined with said coin-carrying section on one side thereof.
